PANEL CRATING STRUCTURE

Leonard W. Johnson and Herbert W. Pottle,
Amesbury, Mass., assignors to The Bailey Company, Inc., Amesbury, Mass., a corporation of Massachusetts

Application October 14, 1948, Serial No. 54,382

6 Claims. (Cl. 206—60)

1

This invention relates to improvements in edge-protecting crating structures for packaging a plurality of wall board panels or the like for shipment. More particularly it provides such a crating structure comprising edge-enclosing channel members having improved means for effecting a secure inter-lock at corner junctures of adjacent channel members.

Heretofore, conventional crating structures for wall board panels have employed metal channels or protectors at only two opposite edges of the crate or package and each of the other two edges has had a relatively thick wooden strip extending therealong to which turned-over tongues on the ends of the metal channels have been nailed to secure the crating elements together. While it has been known to employ channel elements on all four sides of panel crates, with various means for securing the elements together at the corners, the mentioned conventional crating structure having wood strips along two edges has met with considerable favor because of the relative ease of application. However, the use of wood strips sacrifices needed strength, and, the relatively thick wood strips add substantially to the overall dimensions of a crate or package.

It is among the objects of our present invention to provide an all-metal panel-crating structure which adds only slightly to the dimensions of the crated panels per se, and which includes simple and effective means for quickly locking the elements securely at corners of the crate or package.

Another object is to provide panel-crating structural elements which quickly and effectively may be assembled in protecting and holding relation to an assemblage of panels without any securing means penetrating the panels, and without need for any extraneous securing means which are not integral parts of the crating structure.

A further object is to provide a pair of similar panel-crating elements each adapted to extend integrally in protective and holding relation to two adjacent side edges of an assemblage of panels, and including interlocking means for securing the two elements at only two corners of the crate.

It is, moreover, our purpose and object generally to improve upon prior panel-crating structures.

In the accompanying drawings:

Fig. 1 is an elevation of a crate or package of panels embodying features of the invention;

Fig. 2 is a perspective view of one of two opposite channel elements of the crate of Fig. 1;

2

Fig. 3 is a perspective view of one of the other two opposite channel elements of the crate of Fig. 1;

Fig. 4 is a fragmentary perspective view of one corner portion of the crate of Fig. 1, showing the interlocking tongues on the respective channel elements at an intermediate stage of locking;

Fig. 5 is a view similar to Fig. 4 but showing the corner lock at a completed stage;

Fig. 6 is a cross-sectional view on line 6—6 of Fig. 5;

Figs. 7, 8 and 9 are fragmentary perspectives of one corner region of a crate as illustrated in Fig. 1, but showing modified forms of the tongue on one of the channel elements;

Fig. 10 is a fragmentary perspective view of a modified form of channel element;

Fig. 11 shows, in perspective, end portions of two inter-fitting channel elements having a modified form of inter-locking means, the channel elements being shown in separated relation;

Fig. 12 is a fragmentary elevation of the channel elements of Fig. 11 assembled and locked together;

Fig. 13 is a view generally similar to Fig. 12, but showing channel elements of equal width having mitered end juncture;

Fig. 14 is a fragmentary perspective view of an end portion of a channel element having yet another modified form of locking tongues;

Fig. 15 is a fragmentary perspective view of a corner region of a crate of panels with the channel elements locked together by means including the tongues of Fig. 14;

Fig. 16 is a fragmentary elevation of a structure generally similar to that of Fig. 15, but showing channel elements of equal width mitered at their end juncture;

Fig. 17 is an elevation of a crate of panels showing a crating structure having only two channel elements and only two corner interlocks;

Fig. 18 is a perspective of one of the channel elements of Fig. 17, showing in dotted lines one-half of the element bent into right angular relation to the other half; and

Figs. 19, 20 and 21 are fragmentary perspectives illustrating modified forms of structure for the mid-region of bending in a channel element of the type shown in Fig. 18.

Referring to the drawings, and more particularly to the embodiment of the invention as represented in Figs. 1-6, four rectangular panels are shown at 10 indicative of panels of any suitable number and size which are to be packaged or crated as a unit for shipment. Two similar

sheet metal channel elements 12 are adapted to engage over two opposite edges of the assemblage of panels, and two similar sheet metal channel elements 14 are adapted to engage over the other two edges of the assemblage of panels.

According to the invention, each channel element 12, at each end thereof, has a portion of the bottom wall of the channel cut away as at 16 whereby the channel side walls project substantially beyond the bottom wall at each end of the element, as best seen in Fig. 2, these projecting portions of channel side walls constituting tongues 18 which may be bent inward toward each other for a purpose which later will appear.

Each channel element 14, at each end thereof, has a portion of each side wall of the channel cut away as at 20 whereby the channel bottom wall projects substantially beyond the side walls at each end of the element, as best seen in Fig. 3, the projecting bottom wall constituting a tongue 22 at each end of the element which is adapted to be bent to stand flatwise across the end of the channel for a purpose which later will appear.

The length of each channel element 12, 14, excluding the projecting tongues 18 or 22, will approximate the length of the particular panel edges which it is to cover. However, the channel elements 12 are slightly wider than the elements 14 so that the elements can be arranged over the edges of the grouped panels 10 with the end portions of the channel elements 14 engaging within end portions of the channel elements 12 at each of the four corners of the package, and with the tongues 18 and 22 projecting. Then, the tongues 18 at each corner are bent inward against the bottom wall of the adjacent channel element 14, as illustrated in Fig. 4, following which each tongue 22 is bent over upon the tongues 18 to effectively lock the channel elements 12, 14 together at each corner, as illustrated in Fig. 5.

Inasmuch as a package or crate of panels may be relatively large and heavy, it is desirable to have at least one channel element exteriorly smooth along one edge of the package whereby this channel element can serve as a rail on which the package may be slid on edge during handling of the package or crate. Our improved channel elements and corner locks are designed so that either of the two channel elements 12 can serve as a smooth sliding rail, the main bodies of the three tongues at each corner being out of the plane of the exterior edge surface of the package. However, as best seen in Figs. 5 and 6, the rounded base portion 23 of each turned over tongue 22 stands close to the cut end of the bottom wall of channel elements 12 preventing any substantial cutting or "digging in" action at these end regions during handling of the package or crate.

When crating the panels 10, the assembled panels conveniently may be supported in a generally horizontal plane with their edges free to receive the channel elements which latter quickly and easily may be applied and locked at the corners without any element penetrating the panels. The tongues 18, 22, by strokes of a hammer, or the like, may be bent to their retaining interlocked relations as illustrated in Fig. 5, and each channel element 12, 14 engages directly against the edges of the panels whereby the completed package or crate has dimensions only slightly greater than the panels. This is of prac-

tical importance as compared with conventional panel crating structures which require relatively thick wooden strips at the opposite ends of the package or crate which add from four to eight inches to the over-all length, an item which materially increases shipping space requirements as well as providing a weaker structure as compared with the structures herein disclosed.

Figs. 7, 8 and 9 show modifications of the Figs. 1-6 structure in which the tongues 22' have extra length for engaging under the end-most baling wire 24 which ordinarily is wrapped around the completed crates to further strengthen the packages. In Fig. 7, each tongue 22' has its end portion preliminarily formed to provide the seating groove 26 for a baling wire. By this means, the baling wire is maintained by the tongue against slip along the channel elements, and the tongues 22' are retained by the baling wire against accidental dislocation out of locking relation to the tongues 18.

In Fig. 8, the tongues 22' have the extra length as in Fig. 7, but a mound 28 is formed on the channel element 14 in position to be engaged by the end portion of tongue 22'. In this case, the wire seating groove 26 may be formed by hammering the end of the tongue 22' to depress portions between mound 28 and tongues 18.

The modification of Fig. 9 has only the central region 29 of the tongue 22' preliminarily formed to provide a wire-seating groove, the adjacent lateral portions of the tongue being depressed to engage flatwise against the channel element 14.

Fig. 10 illustrates a modified form of the channel elements 12. The main extent of these elements 12', in the Fig. 10 form, may have the same width as the channel elements 14, but the end portions 12'' are expanded to the extra width required to receive the elements 14.

Referring now to Figs. 11 and 12, the channel elements 14, in this form, are similar to the channel elements 14 of Fig. 8, with the extra long tongues 22', but the tongues 22', before associating the channel elements together, are bent from their initial dotted line position in Fig. 11 to the full line position, and the channel elements 12'', in this case, have an out-set integral strip portion near each end of an element 12 providing a slot 30 through which one of the tongues 22' may be inserted. Also, slightly inward of each slot 30, each element 12'' is provided with an out-set mound 32 which cams the end of tongue 22' a little away from the element 12'' as the tongue is forced through slot 30. This automatically locates the end of the tongue in the inclined dotted position thereof in Fig. 12, which facilitates engagement of the tongue end by a hammer or the like to bend it over to its full line position in Fig. 12. Obviously, if desired, the channel element 12'' of Figs. 11 and 12 may have its main extent of the same width as the width of channel element 14, with only its end portions expanded to the needed greater width, comparable to the showing in Fig. 10. By mitering the side walls of the channel elements 12'' and 14', as at 34 in Fig. 13, the entire extents of all channel elements may be of equal widths, this mitering being applicable to the Figs. 1-6 form as well as to the Figs. 7-8 modifications and the Figs. 11 and 12 form.

Instead of forming the slots 30 in the channel elements 12'', as shown in Figs. 11-13, two tongues 36 may be out-set near each end of the element, as illustrated in Fig. 14. Then the

tongue 22' of element 14 or 14' may be arranged between the tongues 36 and the latter bent over upon the tongue 22', with incidental bending of the end portion of the tongue 22' over the mound 32 so that it assumes a position generally the same as its dotted position in Figs. 12 and 13, from which dotted position it conveniently may be bent over upon the tongues 36 as shown in full lines in Fig. 15. Here again, the end portions only of one or the other of the inter-fitting channel elements may be expanded in a manner comparable to the Fig. 10 showing, or the side walls of all channel elements may be mitered as at 34 in Fig. 16 so as to have uniformity of width of all channel elements throughout the extents of their respective channels.

While the channel elements illustrated in Figs. 1-16 have various important advantages over prior comparable panel-packaging and crating structures, we prefer to reduce the number of parts to a practicable minimum by providing only two separate channel elements, each of which engages over the panel edges along two adjacent sides of the package or crate. Fig. 17 illustrates such a package or crate of panels wherein only two channel elements and only two corner locks are required. Both of the channel elements may be identical in structure. In Fig. 18, one suitable channel element structure is portrayed in full line prior to bending of one-half into the right angular relation to the other half, as shown by dotted lines in Fig. 18. The channel portion 40 is adapted to engage over the edges of panels 10 along one side edge of the assemblage of panels, and the integral channel portion 42 is adapted to be bent into right angular relation to portion 40 so as to engage over the edges of the panels along an adjacent side edge of the assemblage of panels. The portion 42, adjacent to the line of bending at 43, is expanded in width as at 44, and the side walls are deeply notched at 46, so that the side walls of the expanded region can swing outside of the side walls of the adjacent portion 40. The free end of portion 40 is formed with the projecting tongue 48, comparable to the tongues 22 on the channel element 14 of Fig. 3, and the free end of portion 42 is formed with the projecting tongues 50, comparable to the tongues 18 on the channel element 12 of Fig. 2. Also, the free end region of portion 42 is expanded in width at 52, comparable to the showing in Fig. 10.

By employing two of the channel elements as shown in Fig. 18, all four edges of an assemblage of panels 10 may be covered, with but two corner locks, as seen in Fig. 17, each of which will be the same as shown in Fig. 5.

Figs. 19-21 show variations of the structure at the region of bending between the portions 40, 42 of the channel element of Fig. 18.

All of the illustrated channel elements may be of suitably rigid sheet metal stock which conveniently may be rolled to shape according to well known metal-forming procedures.

We claim as our invention:

1. A structure for crating rectangular panels, comprising a plurality of sheet metal channel elements adapted to engage over the edges of one or more panels, means at an end of each of two of said channel elements whereby said ends of said two channel elements fit together to provide a right-angular juncture of the elements with the channels open inward, a tongue integral with one of said channel elements at said fitted end thereof, and a generally flat body of metal

at said fitted end of the other channel element, integral with and displaced out of the plane of a wall of said other channel element, said displaced body extending transversely of the general direction of extent of said tongue, said tongue being inserted behind said displaced body and being bent back over upon the said body, thereby to effect a secure inter-lock between the two said channel elements.

2. A structure for crating rectangular panels, comprising a plurality of sheet metal channel elements adapted to engage over the edges of one or more panels, a pair of tongues at an end of one of the channel elements, each said tongue being an integral extension of a side wall of a channel element extending beyond the adjacent end of the bottom wall of said channel element, and said tongues being turned inward into general alignment with each other across the end of the channel and in a plane parallel with and spaced outward from said end of the bottom wall of said channel element, a single tongue on an end of another of said channel elements, said single tongue being an integral extension of the bottom wall of the latter said element extending beyond the ends of the side walls of the latter said element, said single tongue being inserted behind said pair of tongues and bent back over upon said tongues, thereby to effect a positive inter-lock between the two said channel elements.

3. In a crating structure for rectangular panels, two channel elements adapted to engage over two angularly related adjacent side edges of superimposed panels, with ends of said channel elements engaging together at a corner of the panels, means for effecting an inter-lock between said channel elements at said corner, comprising a pair of tongues at the ends of the side walls of one of said elements, said tongues being bent into opposed mutual alignment across an end of the channel of said one element, and a single tongue at the end of the bottom wall of the other channel and inserted behind said pair of tongues and turned back over upon said pair of tongues, whereby said elements are positively locked together at said corner.

4. A structure for crating a plurality of superimposed rectangular panels, comprising two similar channel elements each having length and width of channel for engaging over the full extent of two adjacent edges of the assembly of superimposed panels, means at a mid-location along each of said elements whereby approximately one-half the extent of each element may be bent into generally right angular relation to the other half, with its opposite end portions at two diagonally opposed corners of the panels, a pair of tongues at one end of each of said elements, a single tongue at the other end of each of said elements, said pair of tongues on each element being displaced into alignment across the ends of the respective channels, and said single tongue on each element being inserted behind the pair of tongues on the other element and bent back over upon said pairs of tongues whereby said two channel elements are locked together only at each of said two diagonally opposed corners.

5. In a crating structure for holding and protecting the edges of an assemblage of superimposed rectangular panels, a plurality of sheet-metal channel protectors for engaging over adjacent edges of the assemblage of panels with two of said channel protectors having ends which

come together at a corner of the assemblage of panels, and means at said ends of said two channel protectors for securely locking the channel protectors together at said corner, said locking means comprising a pair of parallel tongues at the end of one of the channel protectors, each tongue being an integral extension of a different side wall of said one channel protector, and said tongues being displaced toward each other across the end of the channel, and a single tongue at the end of the other channel protector, said single tongue being an integral extension of the bottom wall of said other channel protector and being inserted behind said pair of tongues and turned back over upon the outer faces of the pair of tongues, thereby to effect a secure inter-lock between the channel protectors at said corner.

6. In a plural-panel shipping package wherein in a plurality of rectangular panels are in superimposed relation with their respective edges in registering alignment, a sheet-metal edge protector and holder having channel cross-section engaged over and extending throughout the extent of one side edge of the assemblage of panels and, at a corner of said assemblage, sharply bent at a right angle and extending thence throughout the extent of and engaged over another side edge of the assemblage of panels, means at the corner location of said bend adapting the channel portions at opposite sides of the bend to coact in providing right-angular continuity of the channel cross-section at the region of the bend, a second similar sheet-metal edge protector and

holder having channel cross-section engaged over and extending throughout the extent of the other two side edges of the assemblage of panels, said second protector being sharply bent at a right angle at the juncture of said other two side edges, a tongue integral with each said edge protector and holder at one end of each, and a generally flat body of metal at the other end of each edge protector and holder displaced out of the plane of a wall thereof, said displaced bodies extending transversely of the general direction of extent of said tongues, each said tongue being inserted behind a said displaced body and being bent back over upon the said body thereby to effect a secure inter-lock between the two said edge protectors and holders.
